(57) **CLAIM**

The ornamental design for a lawn grooming device with hitch as shown and described.

DESCRIPTION

FIG. 1 is a top perspective view of a lawn grooming device with hitch;

FIG. 2 is a bottom perspective view thereof;

FIG. 3 is a back view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines showing of various portions and other elements in the Figures are for the purpose of illustrating unclaimed portions and form no part of the claimed design.

1 Claim, 6 Drawing Sheets
